WILLIAM T. PURSGLOVE, OF PHILADELPHIA, PENNSYLVANIA, ASSIGNOR TO THE
A. MECKY COMPANY, OF PHILADELPHIA, PENNSYLVANIA, A CORPORATION OF
PENNSYLVANIA.

SEAT FOR VELOCIPEDES AND OTHER VEHICLES.

1,114,648.

Specification of Letters Patent. Patented Oct. 20, 1914.

Application filed March 17, 1914. Serial No. 825,235.

To all whom it may concern:

Be it known that I, WILLIAM T. PURSGLOVE, a subject of the King of Great Britain, residing in the city and county of Philadelphia, State of Pennsylvania, have invented 5 a new and useful Seat for Velocipedes and other Vehicles of the Class, of which the following is a specification.

My invention relates to the seat of a 10 velocipede or other vehicle of the class, and consists in mounting such seat on a resilient device which is so constituted as to provide means for limiting the descent of the seat when occupied, the same also adding to the 15 resiliency of the mounting.

It consists also of details of construction, as will be hereinafter described.

The invention is satisfactorily illustrated in the accompanying drawing, but the important instrumentalities thereof may be varied, and so it is to be understood that the invention is not limited to the specific details shown and described.

Figure 1 represents a bottom plan view of 25 the seat embodying my invention. Fig. 2 represents a side elevation of the same and connected parts. Fig. 3 represents a longitudinal vertical section taken from Fig. 2. Fig. 4 represents a transverse section on the 30 line $x-x$, Fig. 3. Fig. 5 represents a perspective view of a detached portion of the device.

Similar numerals of reference indicate corresponding parts in the figures.

Referring to the drawings:—1 designates 35 the reach, backbone or portion of the frame of a velocipede, the same having connected with it the vertically-extending boss 2, in which is received the stem 3, and which is 40 provided with the screw or bolt 4 for engagement with the side of said stem.

5 designates a spring formed of a plate 45 of resilient metal or material bent on itself into somewhat of the form of a loop, with its limbs extending in comparatively horizontal direction, the lower limb 6 being firmly connected with the upper end of the stem 3, and the upper limb 7 of which is passed freely through the keeper or bridge 8 which is riveted or otherwise connected with the underside 50 of the seat 9 of the velocipede, said keeper having in its lower member the bolt or screw 10, which is adapted to tighten

against the limb, it being noticed that the seat may be moved forwardly or rearwardly 55 and thereby adjusted to the required position, it sliding readily on the limb 7, and when adjusted it will be held and controlled thereat by the keeper and screw or bolt 10, it being noticed that the seat has a portion of its metal or material pressed or otherwise deflected upwardly from its under side, so that the sides and top walls of the deflection which are integral with the adjacent portions of the top of the seat form the 60 longitudinally-extending channel 11 in said underside at the center thereof, the same being adapted to have the limb 7 of the spring seated thereon and serving to guide said seat in its fore and aft adjustments on 65 said spring and prevent wabbling and side play of the seat on the spring, and serving furthermore, to support the top wall of the channel and consequently the seat itself on 70 said spring in a firm and steady manner. 75

Attention is particularly directed to the fact that the rear end 12 of the limb 6 of the spring 5 is continuous rearward of its place of connection with the stem 3 and is free of said connection, it being deflected upwardly and made salient in a direction toward the seat, whereby when the latter is occupied and so loaded, it will descend to said limb 7 and be imposed thereon or abut against the end of the same as a stop limiting its downward motion and providing another resilient support for the same, additional to that afforded by the upper limb 7 and the bend 13 of the two limbs, thus providing great resiliency for the mounting of 90 the seat which will be appreciated by the rider.

The seat 9 is adapted to be adjusted in vertical direction by means of the stem 3 and boss 2, and it is provided with the cover 95 14, as well known, said cover having been removed from Fig. 2.

Having thus described my invention what I claim as new and desire to secure by Letters Patent, is:—

1. In a vehicle, a seat having therein on its underside a channel the upturned walls of which are integral with the adjacent portions of the seat, a resilient member connectible with the frame of the vehicle having 105 a limb adapted to occupy said channel, and

means on the seat adapted to engage said limb for retaining the latter firmly in said channel.

2. A seat for a vehicle of the character stated having in its under side a channel, and a transversely-extending keeper thereunder, a looped shaped resilient member having its limbs comparatively horizontal, the upper limb thereof being adapted to be adjustably fitted in said channel and engaged

tightly by said keeper, and the lower limb adapted to be connected with a member of the frame of the vehicle, said lower limb being extended rearward of its place of connection with said frame and formed salient 15 toward the seat.

WILLIAM T. PURSGLOVE.
